CLAIM

The ornamental design for a water bottle as shown and described.

DESCRIPTION

FIG. 1 is an isometric view of a water bottle showing the new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top view thereof; and,

FIG. 7 is a bottom view thereof.

The broken lines show portions of the water bottle that form no part of the claimed design.
